SUBSTITUTE FOR MISSING OR

X866

PATENTED APR. 29, 1808.

B. DEARBORN.
ANGLET.Solex

1869

App.

Beginning December of 1869.

Sellers, Patent.

The Schedule referred to within Letters Patent and on the front of the
same containing a description in the words of the said Commissioner
Gives back himself of his instrument called the Angle.

This instrument consists of the following parts, viz. 1st Two legs or
bars united by a joint in such a manner as to open and shut like
a jointed stick. 2nd A ruler made to slide over or in one of the
long legs for measurement. 3rd A Prism the two ends of which
have an arc of 90° one end being thereby restricted to one of the legs
the other to the ruler. To the prisms of the following subordinate
parts are added or connected as may be expedient. 4th A ruler ruled
sliding in one or both of the legs above mentioned. 5th A spirit level
either horizontal or inclined. 6th A small scale or circle to ascertain
the distance or number of degrees at which the instrument is spread.
before the index will note the degrees, with accuracy. 7th A mirror
or "rule and prope" weights for the purpose of surveying land &c.
On that leg where the ruler moves a scale is laid down on one or
both sides. Shewing by means of the index at what angle the instrument
is open at any degree from the lowest to the highest marked
distance. On either side. The instrument consists of iron and
such other metals may be used as shall be required for math-
ematical calculations or measurements in any way in which the area
or. chain scales, including Rule, or common rule may be applied.
This instrument may be made of Iron, Brass, Metal or Wood, or any of
these materials may be mixed therein; and it may be of any size
required to suit the purpose for which it is wanted. The largest
which has yet been made of five feet radius, opening to a ten foot pole
the smallest six inches radius opening to a twelve inch stick. In
addition to the purpose above mentioned for which the angle may be
used, it may also be graduated with a scale of equal parts on the legs

800X

one end edge of one leg corresponding with a similar mate on the other leg
and a sliding square or right angle applied thereto will ascertain
the latitude and direction of a Ships course. But a different in-
strument has long been known with a sliding square applied to
the same purpose. Therefore the application of the square in this way
is not considered as being secured by the exclusive right of this Patent.
